FIG. 4

Patented June 12, 1923.

1,458,396

UNITED STATES PATENT OFFICE.

FREDERICK W. CURRIER, OF MINNEAPOLIS, MINNESOTA.

PLATE-GLASS SETTING.

Application filed November 22, 1919. Serial No. 340,057.

To all whom it may concern:

Be it known that I, FREDERICK W. CURRIER, a citizen of the United States, resident of Minneapolis, county of Hennepin, State 5 of Minnesota, have invented certain new and useful Improvements in Plate-Glass Settings, of which the following is a specification.

The object of my invention is to provide 10 means in connection with a glass setting to present a yielding surface to the glass to the end that it may compensate for any inaccuracy in alignment of the setting or any lack of skill on the part of the workmen in placing 15 the glass in the setting, and thereby avoid danger of breakage, which frequently occurs where a metal setting is rigidly clamped to the surface of the glass.

Other objects of the invention will appear 20 from the following detailed description.

The invention consists generally in various constructions and combinations, all as hereinafter described and particularly pointed out in the claims.

25 In the accompanying drawings forming part of this specification,

Figure 1 is a horizontal sectional view through a plate of glass and the settings therefor provided at one side of the window, 30 between abutting plates and at the angle of the window,

Figure 2 is a vertical sectional view showing a setting provided at the lower edge of the plate,

35 Figure 3 is a sectional view taken on the line 3—3 of Figure 2 looking in the direction of the arrow,

Figure 4 is an outside view, showing the discharge openings provided for the passage 40 of the water of condensation,

Figure 5 is a vertical inside view, showing the division bar between the plates of the window,

In the drawing, referring to Figure 1, 2 45 represents a portion of the window frame. 3 is the stop at one side of the window. 4 is the plate of glass to be mounted in the setting and 5 is the rail composed of sheet metal, preferably copper, bent to form the 50 setting and in which the vertical edge of the plate 4 is seated. The rail 5 has a base that is seated against the frame 2 and one part is bent at right angles substantially to the base portion and terminates in a flange 6 that is 55 bent around the edge of the stop 3 and bears

thereon. Near this flange the rail is provided with a substantially dove-tailed recess 7 adapted to receive a correspondingly shaped block 8 of cork or other suitable material having a face to bear on the plate 4 and yield under pressure of the plate thereon. A block 9 is also provided in the rail between which and the vertical edge of the plate a yielding strip 10 is inserted. The outer part of the rail is bent to form a part 60 or flange 11 terminating in a flattened portion 12 which bears on the opposite face of the glass from the block 8. A screw 13 is inserted through the flange 11 into the stop 3, thereby securely locking the rail and the 70 edge of the glass to the stop.

The division bar comprises a plate 14 in which one end of a bolt 15 is mounted and a plate 16 having its edges 16' bent around the corresponding edges of the plate 14 and 75 adapted to bear on one face of the adjacent edges of the glass plates. A plate 17 is provided on the other side of the glass having recesses 18 to receive the blocks 19 of yielding material, which are seated against the 80 other face of the plates. Nuts 20 are provided on the threaded shanks of the bolts 15 for drawing the plates 14 and 17 together to clamp the glass between them, suitable bushings 21 being mounted on the bolt 15 between the plates. A rail 22, preferably of sheet metal, has its edges 23 engaging the flanges 18' of the plate 17 and the outer end of the bolt 15 passes through the rail 22 and is provided with lock nuts 24 for securing 85 the rail firmly to the plate 17 and locking all the parts together.

At the corner of the display window I provide an outer plate 25, angular in form, and a correspondingly shaped plate 26 interlocking with the edges of the outer plate and supporting a bolt 27 which passes through a bushing 28 of yielding material and has its inner end mounted in a rail 29 that is provided with yielding blocks 30 100 which bear on the inner faces of the plates intermediate to the angle between them. This is the corner rail of a glass setting. The blocks 30 are adapted to yield under pressure and adapt themselves to any inequalities of the glass or any lack of alignment of the rails or any carelessness in tightening the bolts of the settings.

In Figure 2 I have shown a sill 31 supporting a rail 32 having an upwardly turned 110

part or flange 33 at its inner edge provided with a recess 34 to receive a yielding block 35 of suitable material, said recess portion of the flange being secured to the inside stop 36 by a screw 37. The part or flange 33 terminates in an edge 38 which is bent inwardly over the stop 36 and has an inclined upper surface for directing the drippings, as in washing the window inwardly toward the glass. The blocks 35 are mounted at intervals, as indicated in Figure 3, so that the moisture can follow the glass down between the blocks and the lower edge of the glass is seated on a yielding block 39 that is carried by a block 40 which rests upon the base of the rail. A series of ports 42 are provided in the walls of the flange 43 which is bent upwardly from the base of the rail and bears on the face of the glass and has holes therein for the reception of screws 41. Spaces are shown provided between the blocks 35 for the passage of the moisture and there is also shown in Figure 3 the ports or openings 42 through which the moisture is discharged on the outside of the window. With this style of glass setting extreme accuracy of alignment of the rails is not necessary, as the blocks will yield and compensate for any slight difference in the surface of the glass and furthermore, inexperienced or careless workmen cannot so readily cramp or put a strain on the glass plates by rigidly clamping the supporting rails thereon, my invention allowing the plates to automatically adjust themselves to any slight variation in the proper relative arrangement of the rails and also offset any extreme or rigid fastening of the rails to the plates.

I claim as my invention:

1. In a window structure or the like a glass setting comprising a rail having a base portion seated against the frame of the window and provided with an upwardly turned part or flange, a block interposed between the edge of the glass and the base of the rail, said upwardly turned part or flange having its edge folded over the adjacent edge of the window frame stop and provided with a recess, a second block fitting within said recess and seated against the inner face of the glass, a second flange on said base bearing against the outer face of the glass and means passing through said flanges and into said stop for drawing said outer flange against the face of the glass and the glass against the second block.

2. In a window structure or the like a glass setting comprising a rail having flanged edges between which the edge of the glass is received and held, one of said flanges having a dovetailed recess formed therein, and blocks mounted at intervals in said recess and bearing on the adjacent face of the glass, the spaces between said blocks forming drainage openings for water and

said rail having discharge ports communicating with said openings.

3. In a window structure or the like a glass setting comprising a horizontal rail having flanged edges between which the edge of the glass is received and held, with gap between the glass and the base of the rail, the inner flange of said horizontal rail having blocks of yielding material mounted therein bearing on the inner face of the glass, said blocks being spaced apart to provide outlets for the water of condensation, the outer flange of said rail having ports communicating with said outlets through the gap beneath the glass for discharging the water of condensation from said outlets.

4. In a window structure or the like a glass setting comprising a rail having a base portion seated against the frame of the window and provided with an inwardly turned flange, a block interposed between the edge of the glass and the base of said rail, said flange having its edge folded over the adjacent edge of the window frame stop and provided with a recess between said stop and the glass, and blocks fitted at intervals in said recess and seated against the glass, the spaces between said blocks forming discharge outlet for water, and means for securing said rail to the window frame stop and pressing the glass against said blocks.

5. In a window structure or the like, a glass setting comprising a rail having a base and inwardly turned flanged edges between which the edge of the glass is received and held, a stop against which one of the flanges of said rail is seated, a block interposed between the base of said rail and the edge of the glass and a screw mounted in the other flange and passing through the first mentioned flange and into said stop, and blocks mounted in said first named flange and bearing against a face of the glass.

6. In a glass setting, a division rail or bar comprising an outer plate, an inner plate having dovetailed recesses therein, a bolt mounted in said outer plate and adapted to pass between the adjacent edges of a pair of glass plates, and through said inner plate, and blocks of yielding material carried by the recesses of said inner plate and adapted to bear on the surface of the said glass plates.

7. A glass setting comprising an outer plate, an inner plate and blocks mounted in said inner plate for bearing on the inner surfaces of a pair of plates of glass, said inner plate being adapted to provide dovetailed recesses for holding said blocks, a rail having longitudinal edges partially surrounding the walls of said dovetailed recesses and a locking bolt passing through said rail and through said inner and outer plates and securing them all together.

8. A glass setting comprising an outer

corner plate, an inner rail formed to fit the angle of the corner and having a dovetailed recess therein, a yielding block mounted in said recess to bear on the inner surface of 5 the glass, and bolts mounted in said inner rail and the said outer plate for drawing the block and said plate against the inner and outer surfaces of the glass.

9. In a window structure or the like a 10 glass setting comprising a rail seated on the window frame and having upwardly turned flanges between which the edge of the glass is inserted, blocks seated on the base of the rail and supporting the glass, the outer 15 flange of said base being folded inwardly to bear upon the outer surface of the glass and having drainage openings in its lower wall, the inner flange being provided with a recess and blocks fitting therein and seated 20 against the inner face of the glass, said inner flange blocks being arranged at intervals to provide water outlets between them, and means for drawing said flanges together to seat said outer flange and said blocks 25 against the glass.

10. In a window structure or the like a 30 glass setting comprising a rail having a base portion seated against the frame of the window and provided with inwardly turned flanges between which the edge of the glass is inserted, a block interposed between the edge of the glass and the base of said rail, the outer flange of said base being seated 35 against the outer face of the glass, the inner flange of said base having its edge folded over the adjacent edge of the window frame stop and provided with a recess between said stop and the glass, and a block fitting within said recess and seated against the 40 glass opposite the bearing point of said outer flange, and means passing through said flanges and into said stop for drawing said outer flange and said block against the faces of the glass.

45. 11. In a window structure or the like a 50 glass setting comprising a rail having a base seated against the frame of the window and provided with flanges between which the edge of the glass is inserted, blocks interposed between said base and the edge of the glass, the outer flange of said base being folded to bear against the outer surface of the glass, the inner flange having its edge folded over the adjacent edge of the window 55 stop and provided between said stop and the glass with a dovetailed recess, blocks fitting within said recess and bearing on the adjacent surface of the glass, opposite the bearing point of said outer flange, and means

for drawing said flanges together to clamp 60 them and said blocks against the glass.

12. In a window structure or the like a 65 glass setting comprising a rail having a base portion seated against the frame of the window and provided with inwardly turned flanges between which the edge of the glass is inserted, a block interposed between the edge of the glass and the base of said rail, the outer flange of said base being seated 70 against the outer face of the glass, the inner flange of said base having a recess therein and a block fitting within said recess and seated against the glass opposite the bearing point of said outer flange, and means passing through said flanges for drawing said outer flange against the face of the glass and the glass against the last mentioned block.

13. In a window structure or the like a 80 glass setting comprising a rail having a base portion seated against the frame of the window and provided with flanges, a block interposed between the edge of the glass and the base of the rail, the space between said edge and said base portion providing a drainage 85 passage beneath the glass, blocks mounted at intervals in one of said flanges and seated against the inner face of the glass, the spaces between said blocks forming outlets for the passage of the water of condensation, said outlets leading to the drainage passage beneath the glass, and means for drawing the other flange against the face of the glass and the glass against said blocks.

14. A glass setting adapted to receive a 90 sheet of glass including a base portion, an inner flange with a wall adapted to be disposed substantially parallel with the inner face of the glass, said flange having a groove 95 therein, spaced blocks in said groove having faces extending beyond said flange wall to 100 separate said wall and glass, the spaces between contiguous blocks and between the glass and flange providing water outlets, and means to clamp the glass against said blocks.

15. In a window structure or the like a 105 glass setting adapted to receive a sheet of glass including an inner part or strip adapted to extend back over the window stop and having a longitudinal groove therein, a block seated in said groove and having a face to bear on the inner surface of the glass, said block being sufficiently thick to separate said part or strip and glass, and means for clamping the glass against said block.

In witness whereof, I have hereunto set 110 my hand this 13th day of November, 1919.

FREDERICK W. CURRIER.
